(57) CLAIM

I claim the ornamental design for a baby bottle brush, as shown and described.

DESCRIPTION

FIG. 1 is front elevational view of a baby bottle brush, the broken lines showing a shaft and opposing brush heads being included to illustrate portions of the article that form no part of the claimed design; and,

FIG. 2 is a side elevational view thereof.

1 Claim, 1 Drawing SheetFIG. 1

FIG. 2
